2 SHEETS—SHEET 2.

UNITED STATES PATENT OFFICE.

WILLIAM H. NORRIS, OF OAKDALE, LOUISIANA, ASSIGNOR OF ONE-HALF TO RICHARD C. BOND, OF OAKDALE, LOUISIANA.

CLAMPING-BENCH.

1,361,284.

Specification of Letters Patent.

Patented Dec. 7, 1920.

Application filed February 11, 1920. Serial No. 357,937.

To all whom it may concern:

Be it known that I, WILLIAM H. NORRIS, a citizen of the United States, residing at Oakdale, in the county of Allen and State 5 of Louisiana, have invented certain new and useful Improvements in Clamping-Benches, of which the following is a specification, reference being had to the accompanying drawings.

10 This invention relates to certain improvements in clamping benches and has relation more particularly to a device of this general character especially designed and adapted for use in the making of grain 15 doors or the like, and it is an object of the invention to provide a device of this general character having novel and improved means whereby the boards or lumber may be effectively held in assembled relation to 20 facilitate the nailing or kindred operation.

Another object of the invention is to provide a novel and improved device of this general character wherein two relatively movable clamping members are disposed 25 over the working face of the bench and wherein means are provided for causing said clamping members to move one toward the other to engage the work and to maintain the parts thereof in assembled relation.

30 The invention consists in the details of construction and in the combination and arrangement of the several parts of my improved bench whereby certain important advantages are attained and the device 35 rendered simpler, less expensive and otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:

45 Figure 1 is a view in top plan of a clamping bench constructed in accordance with an embodiment of my invention;

Fig. 2 is a vertical sectional view taken substantially on the line 2—2 of Fig. 1;

50 Fig. 3 is an enlarged view in end elevation, with a portion broken away, of the bench as illustrated in Fig. 1;

Fig. 4 is a fragmentary view partly in

elevation and partly in section showing the nail box in a second position;

55

Fig. 5 is a fragmentary side elevational view, illustrating a rack comprised in the invention as herein disclosed; and

Fig. 6 is a fragmentary view partly in elevation and partly in section, illustrating 60 a slightly modified form of the invention.

As disclosed in the accompanying drawings, B denotes a bench of desired dimensions and configuration and which is supported at its opposite end portions by the 65 legs or standards 1. The upper end portions of the standards 1 at each end of the bench B are connected by the transversely disposed plates or planks 2 while the lower portions thereof are connected by the transversely disposed member 3. Depending from each longitudinal marginal portion of the bench B and extending entirely therealong is an apron or plank 4.

Extending longitudinally of the bench B 75 and overlying the adjacent marginal portion thereof is a clamping member 5 and coacting with the opposite longitudinal marginal portion of the bench B and extending substantially entirely therealong is 80 a second clamping member 6 which normally has its opposite end portions rested upon the outstanding wings or extensions 7 at the adjacent ends of the plates or planks 2.

Overlying the outer face of the lower portion of each of the plates or planks 2 and spaced therefrom is a transversely disposed member 8 and disposed between said plate or plank 2 are the vertically disposed rock levers 9 pivotally supported at a desired distance intermediate their ends by the pins 10 engaged with said member 8 and the plate or plank 2 and bridging the space therebetween. The lower end portions of the rock levers 9 are connected by a retractile member 11, herein disclosed as a coil spring and which serves to substantially constantly urge the upper end portions of the levers 9 in a direction one away 100 from the other.

Secured to the opposite end portions of the clamping member 5 are the longitudinally disposed members 12, preferably metallic, and which extend beyond the adjacent ends of said member 5. The outer ex-

tremity of each of the members 12 is continued by a downwardly directed portion or extension 14, terminating in an inwardly directed and substantially horizontally disposed arm 15. The free end portion of the arm 15 is pivotally engaged, as at 16, with the upper end portion of the adjacent lever 9.

Secured to the opposite end portions of the clamping members 6 are the longitudinally disposed members 17, preferably metallic, and which also extend beyond the adjacent ends of said member 6. Each of the members 17 has its outer end portion continued by a downwardly disposed portion or extension 18, terminating in an inwardly directed arm 19, said arm 19 being herein disclosed of a length materially greater than the length of the arm 15 hereinbefore referred to. The inner or free end portion of the arm 19 is provided with a plurality of longitudinally spaced openings 20 whereby the upper end portion of the adjacent rock lever 9 may be pivotally engaged therewith at different points as the occasions of practice may require. In other words, the pivotal connection 21 between each of the arms 19 and the coacting rock lever 9 may be adjusted longitudinally of said arm 19.

Overlying the outer face of each of the members 3 but spaced therefrom is the transversely disposed member 22 and between said members 3 and 22 the lower portions of the rock levers 9 are also directed, said levers 9 being preferably of a length to terminate below the members 3 and 22 so that no obstruction or hindrance will be offered to the action of the retractile member 11 coacting with each pair of levers 9.

The members 3 and 22, at a point substantially midway between the levers 9, rotatably support a stub shaft 23 extending beyond the outer face of the cross member 22. Keyed or otherwise fixed at substantially its center through the shaft 23 and between the members 3 and 22 is an arm 24 having its opposite ends provided with the reversely related but substantially duplicate cam edges 25 which engage the adjacent levers 9 and which levers 9 are maintained substantially constantly in contact with the cam edges 25 through the medium of the retractile member 11.

Keyed or otherwise fixed to the extended portion of the stub shaft 23 is an end portion of an elongated arm or lever 26 of a length to extend beyond the forward side of the bench B. The arm or lever 26 is adapted to be depressed by the foot of the operator and which downward movement of said arm or lever 26 causes the cam edges 25 of the coacting arm 24 to impart relative separating movement to the adjacent rock levers 9, resulting in an inward movement

of the clamping members 5 and 6 whereby the same will be caused to effectively engage the work placed upon the bench B between said members 5 and 6. The work preferably comprises the boards or planks embodied in a grain door structure and said members 5 and 6 hold such clamps or boards in assembled relation with respect to the cross members or cleats so that said boards or planks and cleats may be readily secured one to the other by nails or kindred fastening members.

27 denotes a rack of a conventional type secured to the forward end portion of a member 3 and which is adapted to engage an inwardly disposed part (not shown) carried by the adjacent arm or lever 26 whereby said arm or lever 26 may be held in desired lowered position so that the clamping members 5 and 6 may be held in proper engagement with the work during the nailing or kindred operation.

After the door or the work upon the bench B has been completed, it is only necessary to release the arm of lever 26 and move the same upwardly whereupon the retractile member 11 coacting with each pair of levers 9 will impart automatically separating movement to the clamping members 5 and 6 so that the work may be readily removed.

One end portion of the bench B at a point between the clamping members 5 and 6 is provided with the upstanding cleat or strip 28, preferably at the left end of the bench B. This cleat or strip 28 serves as a stop in loading or positioning the lumber on the bench B whereby the assembly of the door or other work is materially facilitated.

I also find it of importance to provide the upper/portion of the cleat or strip 28 at its central part with the longitudinally disposed elongated notch or recess 29 to facilitate the engagement of the completed door or other work by the hand of the operator when it is desired to remove such door or other work from the bench.

Secured to the central portion of the forward side apron or plank 4 is a pair of longitudinally spaced and outstanding brackets 30 upon which normally rests a box 31 adapted to contain a supply of nails or kindred fastening elements. Each end portion of the box 31 is provided with a depending flange 32 extending transversely thereof and the forward end portion of each of said flanges 32 is pivotally connected through the medium of the pintle 33 with the forward end portion of each of the brackets 30. By this means, the box 31 may be readily tilted forwardly and downwardly, as illustrated in Fig. 4, when it is desired to empty the box 31.

In the form of my invention illustrated in Fig. 6, the lower portion of each of the rock levers 9^a is provided with a plurality

of longitudinally spaced anti-friction members 34 herein disclosed as rollers and with which the cam edges 25^a of the arm 24^a are adapted to engage so that the edges 25^a may 5 coact with the levers 9^a in a minimum of frictional resistance.

From the foregoing description, it is thought to be obvious that a bench constructed in accordance with my invention 10 is particularly well adapted for use by reason of the convenience and facility with which it may be assembled and operated, and it will also be obvious that my invention 15 is susceptible of some change and modification without departing from the principles and spirit thereof, and for this reason I do not wish to be understood as limiting myself to the precise arrangement and formation of the several parts herein shown in 20 carrying out my invention in practice except as hereinafter claimed.

I claim:—

1. A device of the character described comprising, in combination, a bench, relatively movable elongated clamping members coacting with the working face of the bench, members carried by the opposite end portions of the clamping members and extending therebeyond, said last named members being continued by inwardly directed 25 arms, rock levers pivotally engaged with 30

the arms and arranged in pairs, a cam interposed between each pair of rock levers for imparting movement to said levers in unison but in opposite directions, means for 35 rotating the cam member, and a spring connecting the levers of each pair for constantly urging the levers in a direction toward the cam.

2. A device of the character described 40 comprising, in combination, a bench, relatively movable elongated clamping members coacting with the working face of the bench, members carried by the opposite end portions of the clamping members and extending therebeyond, said last named members being continued by inwardly directed arms, rock levers pivotally engaged with the arms and arranged in pairs, a cam interposed between each pair of rock levers for imparting movement to said levers in unison but in opposite directions, means for 45 rotating the cam member, and a spring connecting the levers of each pair for constantly urging the levers in a direction toward the 50 cam, the connection between a lever of each pair with its coacting arm being adjustable in a direction longitudinally of said arm.

In testimony whereof I hereunto affix my signature.

WILLIAM H. NORRIS.
